United States Patent Office

Des. 222,116
Patented Sept. 28, 1971

222,116

EYEGLASSES

Fernando Fallik, Buenos Aires, Argentina, assignor to
Ruth Nehmad, Buenos Aires, Argentina

Filed Apr. 15, 1970, Ser. No. 22,437

Claims priority, application Argentina Oct. 24, 1969

Term of patent 14 years

Int. Cl. D16—06

U.S. Cl. D57—1

FIG. 1

FIG. 2

FIG. 3

FIG. 1 is a perspective view of a pair of eyeglasses showing my new design;

FIG. 2 is a front elevational view thereof, the rear having the same appearance;

FIG. 3 is a sectional view taken on line 3—3 of FIG. 2.

The essential feature of the design resides in the hollow transparent lenses partially filled with a liquid visible through the lenses.

I claim:

The ornamental design for eyeglasses, as shown and described.
